United States Patent Office.

HIRAM W. HAYDEN, OF WATERBURY, CONNECTICUT, ASSIGNOR TO HOLMES,
BOOTH & HAYDENS, OF SAME PLACE.

Letters Patent No. 97,773, dated December 14, 1869.

LAMP.

The Schedule referred to in these Letters Patent and making part of the same.

To all whom it may concern:

Be it known that I, HIRAM W. HAYDEN, of Waterbury, in the county of New Haven, and State of Connecticut, have invented an Improvement in Lamps; and I hereby declare the following to be a correct description of the same.

The object of this invention is to simplify the construction of lamps, and render them more durable and strong, and less costly.

The lamps heretofore constructed, of this class, are made with the different parts united by lips and flanges that are difficult to make and put together, and are liable to become injured in use, especially from the strain of screwing the burner upon the reservoir.

My invention relates to a cylindrical air-distributer, with a guide-socket at the lower end, and a flange projecting to receive the chimney-holder and springs, the said cylinder, guide-socket, and flange being made out of one piece of metal, pressed up by dies, so as to lessen cost and make a better article.

In the drawing—

Figure 1 is a vertical section of my improved lamp, and

Figure 2 is an inverted plan of the upper and removable portion of the burner.

a is the wick-tube, passing through the cap *b*, that is adapted to being screwed upon the fountain, and contains the wick-raiser *c*.

The cylinder *d* is perforated with numerous small holes, and forms the air-distributer.

At the bottom is the flange *e*, to which the chimney-holder or springs *f* are riveted; and within the lower end of this cylinder *d* is the guide-socket *g*; and

at the top of the cylinder *d* is the compound dome *h* *i*, the portion *h* having the flame-slot, and the portion *i* being made with notches *o* around its edge, to admit air between the dome and chimney.

The cylinder *d* is pressed up in dies to the shape, or nearly so, shown in Figure 3; then the flange is made by spreading the metal and shaping the socket, as in Figure 4.

The slot *l*, in the socket *g*, for the wick-tube, and the perforations in the cylinder *d*, are made, and the upper end of the cylinder *d* is attached within the dome *i*.

By this construction the lamp-burner is made very strong at the part most exposed to injury from the strain in screwing the burner upon the reservoir, or lifting off the upper portion of the burner for trimming or lighting.

I claim, as my invention—

1. The perforated cylinder *d*, and guide-socket, made of one piece of metal, and removable from the wick-tube, as and for the purposes specified.

2. The perforated cylinder *d*, flange *e*, and guide-socket, in combination with the chimney-holder, attached to the flange *e*, as set forth:

3. The perforated cylinder *d*, guide-socket *g*, flange *e*, and chimney-holder *f*, made as specified, in combination with the compound dome *h* *i*, with flame-slot and notches *o* *o*, as and for the purposes set forth.

Signed by me, this 1st day of October, A. D. 1869.

H. W. HAYDEN.
